UNITED STATES PATENT OFFICE.

GEORGE A. BEARDSLEY, OF EAST ORANGE, AND DANIEL WARDELL, OF NEWARK, NEW JERSEY, ASSIGNEES TO HAZEL-ATLAS GLASS COMPANY, OF WHEELING, WEST VIRGINIA, A CORPORATION OF WEST VIRGINIA.

VACUUMIZING MACHINE.

Application filed June 20, 1922. Serial No. 569,695.

To all whom it may concern:

Be it known that we, GEORGE A. BEARDSLEY and DANIEL WARDELL, both being citizens of the United States, and residing, respectively, in East Orange and Newark, Essex County, New Jersey, have jointly invented new and useful Improvements in Vacuumizing Machines, of which the following is a specification, reference being had to the accompanying drawings, in which—

Fig. 1 is a side elevation of our improved machine showing the right-hand and left-hand cylinders in section; Fig. 2 is the opposite side elevation thereof; Fig. 3 is the front elevation thereof; Fig. 4 is a section with the parts in the position in which a receptacle is about to be ejected from vacuumizing position; Fig. 5 is a section similar to Fig. 4 but with a receptacle just being inserted into vacuumizing position; Fig. 6 is a section similar to Fig. 5 but showing a receptacle seated in the vacuumizing chamber; Fig. 7 is a section on lines VII—VII of Fig. 3, but showing the parts on the operating table in the succeeding position in the cycle of operations; Fig. 8 is a section on lines VIII—VIII of Fig. 7; Fig. 9 is a section on line IX—IX of Fig. 1, but with the right-hand vacuumizing cylinder elevated to enclose the receptacle therein; Fig. 10 is a section on lines X—X of Fig. 1, but with the left-hand vacuumizing cylinder in lowermost position; Fig. 11 is an elevation of the exhausting valve mechanism showing all of the left-hand valve mechanism and part of the right-hand mechanism taken from the side opposite that shown in Fig. 1; Fig. 12 is a detail of the valve operating cam; Fig. 13 is a detail of the locking cam for the foot treadle; and Fig. 14 is a detail of a receptacle showing the lid applied thereto.

Our invention relates to sealing jars, tumblers and other receptacles in vacuo, and preferably comprises a duplex machine having a pair of sealing chambers or cylinders into which the receptacles are alternately fed automatically and continuously. To this end our improved machine is designed to advance the receptacles into the sealing chambers, enclose them, move them into sealing position, exhaust and then admit air when necessary to complete the sealing oper-

ation, and withdraw the enclosing means and discharge the receptacles. Our improved mechanism is so designed as to give a long dwell in vacuum and its efficiency is increased by making the vacuum chamber as small as practical, so that the minimum amount of air need be exhausted. Our invention also consists in the various features which we shall hereinafter describe and claim.

Referring to the drawings, we have shown a duplex machine in which the numeral 2 indicates the frame of the machine and 3 the table across which the receptacles are moved by the various operations later to be described. The machine is operated by means of four cams, A, B, C and D, mounted on the shaft 4, which is driven from any suitable source of power, such as the pulley 5, to which the shaft is connected through the cone clutch 6 and the gearing 6^a, 6^b, 6^c and 6^d, as is shown in Figs. 1 and 2. As there are two jar lifting cams A, two cylinder lifting cams B, and two jar feeding cams C, with corresponding parts, only one set of cams will be referred to, it being understood that the second set operates in exactly the same way and is indicated by the same reference characters.

The jar lifting cam A, which is best shown in Figs. 2, 4, 5 and 6, operates a bell crank lever 7, at one end of which is a roller 8 which is caused to bear against the normal surface of the cam A and its cam faces 9 and 10 by the spring 11. The opposite end 12 of the bell crank lever 7 is slotted to engage the rod 13, upon the upper end of which the jar supporting disk 14 is mounted. On the rod 13 are the fixed collar 15 and loose collar 15^a, which confine the forked end 12 of the lever 7 between them and so cause the rod 13 to be lifted, and with it the disk 14, when the lever 7 is actuated by the cam surfaces 9 and 10 on the cam A. The collar 15^a is held against the end 12 of the lever by the cushioning springs 15^b, as is shown in Fig. 1.

The cylinder lifting cam B, which is also shown in Figs. 2, 4, 5 and 6, operates a bell crank lever 16, at one end of which is a roller 17, which is caused to bear against the normal surface of the cam B and its cam surfaces 18 and 18^a by the spring 19. The opposite end 20 of the bell crank lever 16

is forked to engage a sleeve 21 which is reciprocably mounted on the rod 13. On the upper end of the sleeve 21 is supported the cylinder 22, which forms the vacuumizing chamber 67, when elevated into engagement with the plate 23, which forms the top of that chamber. To hold the slotted end 20 of the lever 16 in engagement with the sleeve 21, collars 24 and 25 are provided thereon, the collar 25 being yieldingly held in engagement with the slotted end of the lever by a spring 26, which bears against a shoulder 27 on the sleeve.

The jar feeding cam C, which is also best shown in Figs. 2, 4, 5 and 6, operates a bell crank lever 28, at one end of which is a roller 29, which is caused to bear against the normal surface of the cam C and its cam surface 30 by a spring 31. The jar feeding carriage 32 is attached to the long arm of the lever 28 by links 33. The carriage 32 has a depending T-shaped guide 34, as is shown in Fig. 8, which slides in the slots 35 of the jar feeding table 3. Mounted on the rods 36 of the carriage 32 is a saddle 37, which is shorter than the distance between the ends 38 of the carriage and consequently can move relatively to the carriage 32 and between its ends 38 upon the rods 36. Upon the saddle 37 are two pins 39, shown in Figs. 7 and 8, upon each of which is mounted a jaw 40. The jaws 40 are intended to engage the receptacles to advance them into vacuumizing position and each of which also has a forward projection 41 for the purpose of ejecting the receptacle from its vacuumizing position after the lid has been sealed thereon. Carried on the forward end 38 of the carriage 32 are the pins 42, which operate in elongated and diverging slots 43 of the plates 44, which are likewise mounted on the pins 39 and move with the jaws 40. It will be seen that as the saddle moves relatively to the carriage the movement of the pins 42 relative to the slots 43 will cause the jaws 40 to be moved together or apart to engage a receptacle or to be disengaged therefrom, depending on the direction of movement of the carriage and saddle. Intermediate the rods 36 is a stem 45 having a pusher 46 on the end thereof, which engages the rear side of the receptacle and assists in propelling it forwardly along the table into vacuumizing position. On each side of the saddle 37 and spring-mounted therein are the friction slides 47, which by their frictional contact with the table 3 ensure a relative movement between the saddle 37 and carriage 32 and the consequent opening and closing of the jaws 40.

The valve operating cam D, of which there is only one in the machine, and which operates the two exhausting valves 49 and is best shown in Figs. 2, 3, 5, 6 and 12, has an internal cam slot. The internal cam slot has

two normal portions 50 and 51 and two cam portions 50^a and 51^a, which are engaged by the roller 52 on the bell crank lever 53. Attached to the opposite end of the lever 53 is the upwardly extending link rod 54, which is secured to the arm 55, which has a sleeve 56 fixed on the shaft 57. Midway of the shaft 57 and fixed thereto, as is best shown in Fig. 11, is the step cam 58, which engages the step portions of the sleeves 59, arranged either side thereof, and each of which has an arm 60. Spaces are arranged between the steps of the cam 58 and the step portions of the sleeves 59 so as to provide for lost motion in transmitting movement from the shaft 57 to the arm 60 and increase a dwell in the valves as the valve ports are opened respectively to atmosphere and to the vacuum. Attached to each arm 60 is a flexible band 61, the opposite end of which is attached to a drum 62 of a valve 49. Each valve drum 62 has secured to it a spring 63, which rotates the valve drum 62 to open the port 64 to atmosphere when the position of the arm 60 and the flexible band 61 so permits. Each valve 49 is of usual two-way type, which alternately connects the exhausting pump line 65 or the open air port 64 with the port 66. The port 66 leads from each valve 49 to a vacuumizing chamber 67. Each arm 60 is provided with a shoulder 60^a which, as the arm 60 is rocked by the cam 58, comes into engagement with a pin 60^b on the casing of the valve 49 so as to ensure arresting the valve with its port 64 open to atmosphere.

In the upper portion of each vacuumizing chamber is a disk 70, which is supported on a screw shaft 71 depending through the roof of the vacuumizing chamber and by which the disk may be raised or lowered to provide for different heights of receptacles.

The device may be set in operation by depressing the foot treadle 72 against the action of the spring 72^a by which the levers 73, 74 and connecting link 75 are actuated to connect the driving pulley 5 to the shaft 4 through the clutch 6 and the gearing 6^a, 6^b, 6^c, and 6^d. After the machine is in operation the treadle 72 may be locked in depressed position by means of the cam 76, which is operated from the handle 77.

The operation of our improved device is as follows: The machine being set in motion, the operator places a receptacle, with the lid in position thereon, on the table 3 between the jaws 40, as is shown at the right-hand side of Fig. 3. Under actuation from the cam C through the lever 28 and links 33 the carriage 32 advances across the table 3 toward the left-hand side, carrying with it the saddle 37 upon which the jaws 40 are mounted, thus advancing the receptacle upon the disk 14, which, as is shown in Fig. 5, is in lowermost position. The continued rota-

tion of the cam C causes the roller 29 to pass over the cam face 30 and engage the normal surface of the cam, thus permitting the spring 31 to retract the carriage 32 and with it the saddle 37 and jaws 40. As the jaws 40 are retracted the surface 18^a of the cylinder lifting cam B rotates into engagement with the roller 17 and causes the lever 16 to lift the sleeve 21 and elevate the cylinder 22 until its top surface is in engagement with the plate 23, thus forming the air-tight chamber 67, as is shown in Fig. 6. The cam surface 9 on the cam A has also come into engagement with the roller 8 on the lever 7 and caused the disk 14 to be elevated, thus bringing the cap on the receptacle a short distance below the disk 70, as is also shown in Fig. 6, so that as the air is being exhausted from the vacuumizing chamber the cap can not be displaced from the top of the receptacle.

As the cylinder 22 comes into engagement with the plate 23 the roller 52 comes in contact with the cam-portion 50^a of the cam slot of the cam D, as is also shown in Fig. 6, thus rotating the shaft 57 through the lever 53, rod 54, arm 55, and sleeve 56, and causing the cam 58 to rock an arm 60 and rotate the valve drum 62 through the flexible band 61, thus turning the right-hand valve to exhausting position, as is shown in Figs. 6 and 9. As the air is rapidly exhausted from the vacuumizing chamber 67 and from the receptacle, the further rotation of the cam A brings the roller 8 into engagement with the cam surface 10, which forces the rod 13 still further upward and with it the disk 14 and the receptacle thereon so as to bring the cap on the receptacle into engagement with the disk 70, which may be a sealing device of any character, thus forcing, or otherwise securing, the cap firmly on the receptacle. Meanwhile, in the rotation of the cam D the roller 52 rides through the portion 51 of the slot, thus holding the exhausting port 65 open until it comes into contact with the surface 51^a, which permits the roller 52 to drop down, thus bringing the rod 54 and arm 55 into the position shown in Figs. 1 and 11 in which the right-hand valve is open to atmosphere, while the same movement of the shaft 57 has rotated the left-hand valve to exhausting position. As the movement of the cam D rocks the arm 60, the tension on the flexible band 61 is released, which permits the spring 63 to rotate the valve stem 62 in the reverse direction and thereby open the port 64 of the valve to atmosphere. The air then rushes into the vacuum chamber 67 and the cap will then be held on the receptacle by the vacuum inside.

When, as is shown in Fig. 12, the roller 52 is riding through or dwelling in the portion 50 of the cam slot, the arm 55 is held in

lowermost position, as is indicated in Figs. 3 and 5, and the right-hand valve is held open to atmosphere, while the left-hand valve is in exhausting position, as is indicated in Figs. 3 and 11. When the roller 52 rides through the portion 50^a of the slot, the arm 55 is being raised to uppermost position and the right-hand valve is being turned to exhausting position, in which it is maintained while the roller 52 rides through or dwells in the portion 51 of the cam slot, as is shown in Figs. 6 and 9. At the same time the left-hand valve is rotated to and held at the open to atmosphere position, as is shown in Fig. 10.

Further rotation of the cam A retracts the rod 13 and disk 14 to the position shown in Figs. 3 and 4, and at the same time the cylinder lifting cam B has come into engagement with the surface 18, thus permitting the spring 19 to retract the cylinder below the surface of the table 3, thus completing the cycle.

Then when a new receptacle has been placed between the jaws and these jaws are advanced by the action of the jar feeding cam C, the prongs 41 on the jaws will push the filled jar to the left in the succeeding operation, as is shown in the lower side of Fig. 7.

The operation of our improved mechanism is so arranged that as one set of cams A, B and C is causing the apparatus to go through a complete cycle of operations the other set of cams A, B and C is causing the other set to go through a similar cycle, and the cam D simultaneously controls the operations of the valves of both sets, but the movements are so timed that one operator may feed receptacles to both sets of apparatus successively. Thus, as is shown in Fig. 7, while on one side of the machine a receptacle is being discharged and another moved into vacuumizing position, on the other side a receptacle is being vacuumized and another has been placed in position between the jaws 40 ready to be advanced into the vacuumizing position.

Our improved machine is very efficient and smooth in action and after being started runs automatically, the only work required of the operator being to place the receptacles on the feed table between the jaws 40 of the feeding carriage. The operation is substantially without jar, as the movement of the cams A, B and C is against the action of springs, and the upward thrust of the levers actuated by the cams A and B upon the rod 13 and sleeve 21 is cushioned by the springs 15^b and 26. The action of the cam face 9 on the cam A is for the two-fold purpose of lifting the receptacle to such an extent that the exhaustion of the air can not pull the cap off because it is so near the disk 70, and of de-

creasing the amount of lift required to squeeze the cap against the disk 70 and thereby minimize breakage of receptacles.

The length of the dwell of the receptacle in vacuum, which is over 40% of the time required for a complete cycle, also ensures the establishment of an adequate vacuum and therefore the proper sealing of the cap or lid thereon.

10 The terms and expressions which we have employed are used as terms of description and not of limitation, and we have no intention, in the use of such terms and expressions, of excluding any mechanical equivalents of the features shown and described, or portions thereof, but recognize that various structural modifications are possible within the scope of the invention claimed. It is obvious that our improved 15 mechanism may be employed in a variety of operations which it is desirable to carry out under vacuum.

What we claim is:

1. In an automatic vacuum sealing machine for receptacles, a feeding table, a cylinder reciprocably mounted and arranged to be projected above said table to form a portion of a vacuum chamber and to be withdrawn below the level of said table, a 20 reciprocable feeding carriage on said table adapted to feed receptacles into the path of movement of said cylinder and to eject them therefrom, valve mechanism controlling the exhaustion of air from and the admission of air into said vacuum chamber, and driving means having associated therewith a plurality of cams, each of which actuates, through connecting members, a feeding carriage, a cylinder, or the valve 25 mechanism.

2. In an automatic vacuum sealing machine for receptacles, a feeding table, a cylinder reciprocably mounted and arranged to be projected above said table to form a portion of a vacuum chamber and to be withdrawn below the level of said table, a reciprocable feeding carriage on said table adapted to feed receptacles into the path of movement of said cylinder and to eject them therefrom, a receptacle lifting plate within said cylinder, valve mechanism controlling the exhaustion of air from and the admission of air into said vacuum chamber, and driving means having associated therewith a plurality of cams, each of which actuates, through connecting members, the feeding carriage, the cylinder, the receptacle lifting plate, or the valve mechanism.

3. In an automatic vacuum sealing machine for receptacles, a feeding table, a cylinder reciprocably mounted and arranged to be projected above said table to form a portion of a vacuum chamber and to be withdrawn below the level of the table, a reciprocable feeding carriage on said table adapt-

ed to feed receptacles into the path of movement of said cylinder and to eject them therefrom, a receptacle lifting plate within said cylinder, valve mechanism controlling the exhaustion and admission of air into said vacuum chamber, and driving means having associated therewith a plurality of cams, each of which actuates through connecting members the feeding carriage, the cylinder, the receptacle lifting plate or the valve mechanism, the cam actuating the receptacle lifting plate having two cam surfaces, the first being to lift the plate to exhausting position and the second to elevate it still further to sealing position.

4. In an automatic vacuum sealing machine for receptacles, a feeding table, a cylinder reciprocably mounted and arranged to be projected above said table to form a portion of a vacuum chamber and to be withdrawn below the level of the table, a receptacle lifting member operating in said cylinder, and means for lifting said member into exhausting position and subsequently into sealing position.

5. In an automatic vacuum sealing machine for receptacles, a feeding table, a cylinder reciprocably mounted and arranged to be projected above said table to form a portion of a vacuum chamber and to be withdrawn below the level of the table, a receptacle lifting member operating in said cylinder, a sealing member on the upper portion of said chamber, and means for lifting the receptacle lifting member into exhausting position and subsequently lifting the receptacle lifting member to a further extent to press the lid or cap on the receptacle against the sealing member.

6. In a duplex automatic vacuum sealing machine for receptacles, a feeding table, open ended cylinders reciprocably mounted and arranged to be projected above said table and to form with suitable closures vacuum sealing chambers and to be withdrawn below the level of said table, reciprocable feeding carriages on said table each adapted to feed receptacles successively into the path of movement of a cylinder and to eject them therefrom, valve mechanism controlling the exhaustion of air from and the admission of air into said vacuum chambers, and driving means having associated therewith a plurality of cams, each of which actuates, through connecting members, a feeding carriage, a cylinder, or the valve mechanism.

7. In a duplex automatic vacuum sealing machine for receptacles, a feeding table, open ended cylinders reciprocably mounted and arranged to be projected above said table and to form with suitable closures vacuum sealing chambers and to be withdrawn below the level of said table, reciprocable feeding carriages on said table each

- adapted to feed receptacles successively into the path of movement of a cylinder and to eject them therefrom, valve mechanism controlling the exhaustion of air from and the admission of air into said vacuum chambers, said valve mechanism comprising a two-way valve for each vacuum chamber, each valve having a valve drum actuated through a connection with a rocking shaft, a retarding element being interposed between the shaft and each valve drum to give the valve a long dwell in exhausting position, and driving means for cylinders, carriages and rocking shaft.
8. In a duplex automatic vacuum sealing machine for receptacles, a feeding table, open ended cylinders reciprocably mounted and arranged to be projected above said
- table and to form with suitable closures vacuum sealing chambers and to be withdrawn below the level of said table, reciprocable feeding carriages on said table, each adapted to feed receptacles successively into the path of movement of a cylinder and to eject them therefrom, valve mechanism controlling the exhaustion of air from and the admission of air into said vacuum chambers, a driving member, a driven shaft having mounted thereon a plurality of cams for actuating the various actuated members, and a clutch connecting the driving member and the driven shaft, said clutch being under control of a lever and means for locking the lever in operating position.
